UNITED STATES PATENT OFFICE.

FREDERICK H. RYAN, OF BOSTON, MASSACHUSETTS.

MACHINE FOR SHARPENING RAZORS AND OTHER EDGE-TOOLS.

1,148,462.

Specification of Letters Patent.

Patented July 27, 1915.

Application filed February 28, 1914. Serial No. 821,666.

To all whom it may concern:

Be it known that I, FREDERICK H. RYAN, a subject of George V, King of Great Britain and Ireland, and a resident of Boston, 5 in the county of Suffolk and State of Massachusetts, have invented a new and useful Improvement in Machines for Sharpening Razors and other Edge-Tools, of which the following is a specification.

10 I have shown my invention embodied in a machine for sharpening a razor blade of the well known Gillette construction, but it may be embodied in other forms depending upon the blade or tool which is to be sharpened by it. I have also shown my machine arranged with a hone or stone, but it may be used with other sharpening means.

My invention will be understood by reference to the drawings, in which—

20 Figure 1 is a plan, and Fig. 2 a side elevation of a device embodying my invention; Fig. 3 being a section on line 3—3 of Fig. 1, and Fig. 4 being a cross section on line 4—4 of Fig. 1.

25 In its preferred form my invention comprises a bed having a bottom plate A and two side walls A¹, A². Within this bed as shown is mounted a hone B or the like of any suitable material, the whole being supported upon suitable feet C which are preferably made of rubber and are attached to the under side of the plate A of the frame by screws c. Each side wall A¹, A² preferably extends slightly above the upper surface of the hone B and is slotted as at a to receive the axle F of the blade holder. To turn this shaft it carries friction wheels of some character which run upon suitable runways, one located on each side of the bed.

40 As shown these runways are in the form of racks D, one attached to each of the side walls A¹, A², the tops of the teeth of each being approximately on the level of the bottom wall of the adjacent slot a; and the

45 friction wheels are in the form of pinions G.

The blade holder comprises a handle E which is forked, having two arms e; the outer end of each arm is perforated to receive the ends of the axle F. This axle thus 50 extends across the device and projects through the slots a in the side walls A¹, A². Just outside the walls A¹, A² the axle is reduced in diameter so that shoulders f are formed and on each reduced portion f¹ of the axle is carried a pinion G which engages one of the racks D. These pinions

are adapted to turn freely on the axle F except as they are held in frictional contact with the shoulders f by means of springs g and set nuts g¹. By means of these set nuts 60 this frictional contact with the shoulders f may be adjusted.

The axle F is perforated as at h to receive the shank h¹ of the blade clamp. The blade clamp comprises two members, a base plate 65 or member H to which the shank h¹ is permanently attached and from which project pins h², and an upper plate H¹ having key-hole slots or openings h³.

It is well known that the Gillette blade 70 has openings in it which coöperate with pins in the razor-holder to center the blade J in proper position in the holder. In the embodiment of my machine shown the pins h² are located with reference to these openings 75 so that the blade J will be properly centered on the blade clamp. Each pin has a head which is slightly larger than its body and the pins project above the blade when it is in place sufficiently to allow the top plate 80 H¹ to slide under the heads. To clamp the blade in the clamp the larger portions of the key-hole slots or openings h³ in the top plate H¹ are caused to register with the pins h² and the plate is dropped into position, 85 the heads of the pins projecting through the openings, after which the top plate H¹ may be pulled laterally to the right by the upwardly-projecting ear or thumb piece h⁴, the narrow parts of the slots or openings 90 h³ will be overlapped slightly by the heads of the pins h², thus retaining the top plate H¹ in clamping position.

The shank h¹ of the blade clamp is threaded so that it may be adjusted in and out in 95 the opening h in the axle F and this threaded shank affords a pivotal connection of the blade clamp with the bar or axle F, so that the said blade clamp may turn slightly and thus automatically adjust itself to any irregularities on the surface of the hone. It 100 is extremely difficult to grind a stone absolutely level however smooth it may be, and this construction allows the blade during the honing operation to adjust itself to these slight differences of level. To enable the blade clamp to be adjusted in or out relative to the bar or axle F, by virtue of the threaded shank h¹, to compensate for different widths of blades, it is necessary to raise 105 the said blade clamp from the hone or body B, having the sharpening surfaces, so that

the said blade clamp may be turned manually to effect the desired adjustment. But in the use of the device the blade clamp will vibrate with the said bar or axle F without turning far enough to disturb such adjustment.

The pinions G serve two purposes. They serve with the axle and the upper wall of the slots *a* to hold the blade in proper relation to the hone and also as friction rolls so that the blade holder may be moved without undue friction from end to end of the bed. In performing their first function when the blade holder reaches the end of its stroke and there is to be a change of direction of movement, the pinions G upon reversing their direction of movement by reason of their frictional contact with the axle F throw the axle over so that the blade reverses its direction of movement and the opposite side of the edge of the blade is ground. When the blade strikes the hone, however, the frictional relation between the pinions and the ends of the shaft allows the pinions to rotate, while the axle is held stationary by the engagement of the blade with the hone. By allowing a little play between the top edge of the slots *a* and the top of the axle it is possible to adjust the axle so that the pinions do not run in teeth exactly opposite each other, and thus perhaps grind the edge of the blade at a slight angle. In certain cases this may be desirable. In any event, as is usual when a hone is used, the blade is drawn in the direction of its edge as shown by the arrows in the drawings, and it is for this reason that my invention is especially adapted for use with a hone of some type. In use therefore the blade is placed upon the under portion H of the clamp in such a way that the pins *h*² project through the openings in the blade. The plate *H*¹ is then slipped over the pins *h*² and by means of the ear *h*⁴ the plate is pushed to the right (see Fig. 1) so that the narrow portions of the openings *h*³ run un-

der the heads of the pins *h*² and the blade is clamped in position. Then by moving the blade holder backward and forward over the stone the honing operation is accomplished. In Figs. 1, 2 and 3 the direction of movement at the time is shown by the arrow. Upon reversal of movement the blade is thrown into the position shown in dotted lines in Fig. 1 and the other side of its edge is ground. When one edge is sufficiently ground the blade is removed and turned to grind the other edge. For the purpose of holding the machine during the grinding operation a handle K may be used, this being attached to one of the walls *A*².

The details of construction of my device may be changed somewhat, the important feature thereof being the adjustable relation of the blade clamp to the shaft, whereby the clamp may adjust itself to a certain extent to the irregularities of the surface of the stone and also may be adjusted in and out from the shaft to compensate for the width of the blade in cases where the blade has been previously ground, and hence has lost a portion of its width.

What I claim as my invention is:—

In a blade sharpener, the combination with a frame adapted to support a sharpening body, of a blade holder comprising a bar or axle extending across the said body, and a blade clamp having a screw-threaded shank by which it is pivotally attached to said bar or axle so that it may turn on an axis at right angles to the length of said bar or axle and thus be adapted to conform automatically to unevennesses of the surface of said sharpening body and which screw-threaded shank permits of adjustment of the said blade clamp in or out relative to the said bar or axle, to compensate for different widths of blades.

FREDERICK H. RYAN.
